LOUIS C. LARSON, OF SAN JOSE, CALIFORNIA

IRONING BOARD

Application filed February 16, 1932. Serial No. 593,376.

It is one object of the invention to provide an ironing board in which all of the extensible supporting parts may be folded flat upon the board and entirely within the boundary thereof.

It is another object to provide a board of the character indicated in which the several supporting parts will automatically assume their proper positions when the main leg is manipulated relative to the plane of the board.

It is also an object to provide a board of the character indicated in which the supporting legs are effectively braced and secured in an extended position when the board is to be used.

Finally, it is an object of the invention to provide an ironing board of the character indicated that will be economical to manufacture; light in weight; of few parts; strong, rigid, and firmly supported when set up for use; collapsible into a flat, compact package when prepared for storing; quickly and easily manipulated when being set up or collapsed; substantial, durable, and highly efficient in its practical application.

In the drawing:

Figure 1 is a perspective view of an ironing board embodying my invention, partly in section.

Figure 2 is a bottom plan view of a portion of the board when collapsed.

In the particular embodiment of the board herein disclosed I show at 1 the board proper, which is of uniform width throughout its length until it approaches one end where it is tapered as at 2.

Mounted upon the under side of the board and spaced a distance back from the end remote from the tapered end, is a bracket 3 with downwardly turned ends as 4.

At 5—5 are shown legs pivotally mounted at their upper ends on the outer sides of ends 4 by means of bolts 6. Also pivotally mounted on bolts 6, but on the inner sides of ends 4, are legs 7—7, these legs being brought together at their outer ends and secured together by a dowel pin 8 to form a single leg 9, this leg being adapted to rest upon the floor under the end 2 of the board.

Pivots mounted upon leg members 7—7 and at corresponding points midway their length, are arms 10—10, the pivotal connections being indicated at 11. These arms are connected near their free ends by a bar 12 and are adapted to swing as a unit in vertical parallel planes whereby to engage the under side of the board 1 when the structure is raised to an operative position.

A spring catch 13 is mounted on the inner side of board 1 in such a position as to engage bar 12 when the structure is raised as described and effectually prevent its collapse.

Pivots mounted on each arm 10, on the outer side thereof and midway its length as at 14, is a bar 15, the other end of said bar being pivotally mounted upon the corresponding leg 5 as at 16, and on the inner side thereof. This bar is so disposed as to be inclined downwardly from its pivotal point 14 to point 16 when the structure is in an operative position.

Mounted crosswise on the under side of the board 1 and substantially midway between legs 5—5 and catch 13, is a bracket 17. To the depending ears 18 of this bracket are pivotally connected as at 19, links 20. Each link 20 is also pivotally connected to the adjacent bar 15 as at 21, the connections of each link 20 being so disposed that the link is inclined 80 backwardly from its top connection 21.

At 22 is shown a small bracket mounted on the under side of board 1, just rearwardly of and flat against bracket 3. To each ear 23 of this bracket is pivotally connected as at 24 a brace 25, the brace being twisted as at 26 and passing downward at an angle and being pivotally connected as at 27 to the leg 5 on the opposite side of the board, and lying in a plane parallel with the rear edges of legs 5.

A short bar 28 having a vertically disposed portion 29 is mounted upon the center of the rear end of the board, and upon its under side as shown. To this portion 29 is pivotally connected as at 30 a brace member 31, this member being twisted as at 32 so that its main portion is disposed at right angles to the pivoted end. The lower end of this member 31 is pivotally connected as at 33 to the overlapping ends of short arms 34, which are in 100

turn pivotally connected to legs 5—5 as at 35.

The several parts described are so arranged and proportioned that when in a collapsed condition the thick supports such as 5, 9, and 10 lie flat against the board 1 with the parts 15 and 20 folded between them, and the parts 25—25 and 31 lying flat upon the supports 5, 9 and 10 as clearly shown in Figure 2. The positions of the pivotal points 24 and 30, and 10 the twisting of the parts 25 and 31 at 26 and 32 respectively are so designed as to permit the several parts to lie flat as described.

To spread the several parts and set the board up as shown, it is only necessary to 15 grasp the leg 9 and the portion 2 of the board and force the same apart, this action operating to spread all of the members into their respective positions without further adjustment than pressing the bar 12 into engagement with the latch 13.

It will be noted that in performing this operation the links 20 can only swing about their fixed pivotal points 19, and the leg 9 can only swing about its fixed pivotal points 25 6, consequently when the leg 9 is swung in the direction indicated by arrow 36 it operates to swing both legs 5 and arms 10 into the extended supporting position through the medium of the connecting bars 15.

When the structure is collapsed all of the movable parts lie within the confines of the board 1, but it is desirable to spread the legs 5 beyond the width of the board when extended, and this is accomplished by mounting the braces 25 as described. This offset mounting of the braces relative to the pivotal mounting of the legs 5 not only causes them to spread the legs but it also provides a spring support against which the several parts must 40 be forced in order to effect engagement of bar 12 with the latch 13.

The legs 5 are further supported and effectually spread and braced by the structure 29—35 which applies a positive leverage that 45 is direct and effective.

In collapsing the structure it is only necessary to disengage the catch 13 from bar 12, whereupon the angular disposition of the several parts will enable the operator to automatically flatten out the whole supporting structure by merely pressing down the one leg 9.

It is to be understood, of course, that while I have herein shown and described but one specific embodiment of the invention, changes in form, construction, and method of assembly and operation may be made within the scope of the appended claims.

I claim:

60 1. An ironing board comprising, a board, a leg structure pivotally mounted thereon and adjacent one end thereof, a second leg structure pivotally mounted thereon adjacent the same end of the board, supporting means 65 pivotally mounted upon one of said leg struc-

tures and adapted to seat against the bottom of the board, rigid means pivotally connecting the first means and the other leg structure, and link means pivotally connected to said rigid means midway their length and to 70 said board.

2. An ironing board comprising, a board, a leg structure pivotally mounted thereon adjacent the rear end thereof, a second leg structure pivotally mounted thereon adjacent the same end of the board and extending 75 forwardly of the latter and of greater length than the first mentioned structure, supporting arms pivotally mounted on the second structure and inclined upwardly and forwardly therefrom when extended, and adapted to engage the bottom of the board, bars pivotally connecting said arms and the first leg structure and inclined downwardly and rearwardly from said arms when extended, and upwardly and forwardly inclined links pivotally mounted on said bars and pivotally connected to said board. 80

3. An ironing board comprising, a board, a pair of leg structures pivotally mounted thereon adjacent one end thereof, one of said leg structures being extended toward the other end of the board, supporting means pivotally mounted on the last mentioned leg structure and adapted to seat against the bottom of the board, means pivotally connected to the said supporting means and to the other leg structure, and means pivotally connected to said board and to said last mentioned means intermediate its length, whereby pivotal movement of one leg structure will automatically actuate the other leg structure and the said supporting means. 90

4. An ironing board including a board, a pair of leg structures pivotally connected to the board adjacent one end thereof, one of said leg structures extending toward the opposite end of the board, supporting means for the board pivotally connected to the last named leg structure, means to effect spreading of the legs of the other leg structure upon movement of the latter to operative position, means pivoted to and connecting said supporting means and said other leg structure, and means pivoted to the board and to said connecting means whereby pivotal movement of one leg structure will automatically actuate the other leg structure and said board supporting means and effect said spreading of said other leg structure. 100
